CONVERSION OF HYDROCARBON OILS

Jacque C. Morrell, Chicago, Ill., assignor, by
mesne assignments, to Universal Oil Products
Company, Chicago, Ill., a corporation of Dela-
ware

Application March 12, 1931, Serial No. 522,147

5 Claims. (Cl. 196—51)

This invention relates to the treatment of hydrocarbon oils and refers particularly to the conversion of relatively heavy oils into lighter and more valuable products.

5 The primary principles of the present invention comprise subjecting a raw oil charging stock to conversion conditions and simultaneously subjecting a different raw oil charging stock together with reflux condensate from the system to 10 independently controlled conversion conditions in the same cracking system. The secondary charging stock may be within the boiling range of gasoline and may be treated specifically to reform the same for the purpose of improving its anti- 15 knock rating.

In its more specific embodiment the invention may comprise subjecting a raw oil charging stock to conversion conditions in a heating element, introducing the heated products into an enlarged 20 reaction zone, withdrawing both liquid and vapors simultaneously from said enlarged reaction zone at a point relatively remote from the point of introduction and introducing them into a separate enlarged zone of vaporizing chamber preferably 25 maintained under reduced pressure and in which vapors and liquid may be separated, withdrawing vapors from said vaporizing chamber and subjecting them to fractionation, subjecting the relatively light fractionated vapors to condensation 30 and cooling and collecting the products, withdrawing the relatively heavy insufficiently converted components of the vapors subjected to fractionation from the fractionating zone and subjecting them together with a separate raw 35 oil charging stock to independently controlled conversion conditions in a separate heating element and introducing the heated oil from said separate heating element into the aforementioned vaporizing chamber or into the reaction 40 zone or partially to both.

As a feature of the present invention all or a portion of the reflux condensate from the fractionator of the system instead of passing through the heating element in which the secondary 45 charging stock is fed may be introduced into the stream of heated oil discharging from said heating element to cool said stream of heated oil to the desired degree prior to its further treatment in succeeding portions of the cracking system.

50 As another feature of the invention, conditions may be so controlled in the vaporizing chamber or enlarged zone of reduced pressure that either a liquid residual product, a carbonaceous residual material or a product of intermediate nature such

as asphalt or asphalt-like material may be produced in this zone.

The attached diagrammatic drawing illustrates one form of apparatus embodying the principles of the present invention. The following description of the drawing embraces also a description of the process of the present invention as it may be practiced in the form of apparatus here illustrated. 5

A raw oil charging stock, hereinafter designated for the sake of convenience as primary charging stock, may be supplied through line 1 and valve 2 to pump 3 from which it may be fed through line 4, valve 5, line 6 and valve 7 into heating element 8 or all or a portion of the primary charging stock instead of passing directly to heating element 8 may pass from pump 3 through line 9, valves 10 and 11, preheating coil 12, line 13, valve 14, line 6 and valve 7 to heating element 8. Preheating coil 12 may be located 10 within fractionator 15 and the oil fed therethrough may be preheated by indirect contact with the relatively hot vapors in the fractionator. A portion of the primary charging stock may, if desired, be fed from line 10 through line 16 and 15 valve 17 directly into fractionator 15 combining 20 therein with the relatively heavy components of the fractionated vapors which may be condensed 25 in this zone and passing therewith to further treatment as will be more fully described later. 30

Heating element 8 may be located in any suitable form of furnace 18 and the primary charging stock fed therethrough may be heated to any desired conversion temperature preferably under a substantial superatmospheric pressure. The 35 heated oil from heating element 8 may pass through line 19 and valve 20 to reaction chamber 21 which is also preferably maintained under a substantial superatmospheric pressure. The pressure employed in chamber 21 may, however, 40 be either substantially the same or lower than that employed in heating element 8. Products from chamber 21 preferably comprising both liquid and vaporous products may be withdrawn through line 22 and valve 23 to vaporizing chamber 24 which is preferably maintained under substantially reduced pressure relative to that employed in chamber 21. Preferably vapors are separated from the residual liquid in chamber 24 45 and the vapors may pass through line 25, valve 50 26, heat exchanger 27 and line 28 into fractionator 15. Heat exchanger 27 may, of course, be by-passed by well known means, not illustrated, if so desired. The relatively light desirable components of the fractionated vapors may pass from 55

fractionator 15 through line 29 and valve 30, may be subjected to condensation and cooling in condenser 31, products from which may pass through line 32 and valve 33 to be collected in receiver 34. 5 Uncondensable gas may be released from receiver 34 through line 35 and valve 36. Distillate may be withdrawn from the receiver through line 37 and valve 38. A portion of the distillate from receiver 37 may, if desired, be recycled, by well 10 known means not illustrated in the drawing, to fractionator 15 to assist fractionation of the vapors in this zone.

A separate charging stock, hereinafter designated for the purpose of convenience as secondary 15 charging stock, may be supplied through line 39 and valve 40 to pump 41 from which it may be fed through line 42, valve 43, heat exchanger 27, line 44, valves 51 and 45, line 46 and valve 47 into heating element 48, which may be located 20 in any suitable form of furnace 68. Preferably this secondary charging stock is lighter in character than the primary stock and may comprise hydrocarbons within the boiling range of gasoline which are treated to reform them or to improve 25 their anti-knock property. All or any desired portion of the secondary charging stock may, of course, be diverted from heat exchanger 27 and passed from line 42 through line 49 and valve 50 into line 44 and thence to heating element 48, as 30 already described. The secondary charging stock, if any, fed through heat exchanger 27, may be preheated by indirect contact with the relatively hot vapors passing from chamber 24 to fractionator 15. It will be understood that the 35 secondary charging stock may, if desired, be preheated by any other well known means.

The relatively heavy insufficiently converted components of the vapors condensed in fractionator 15 may pass through line 52 and valve 53 40 to pump 54 from which they may be fed through line 55, valve 56, line 46 and valve 47 into heating element 48 together with the secondary charging stock introduced into this heating element, as already described. All or any desired portion of 45 the reflux condensate from fractionator 15 may, if desired, be diverted from line 55 through line 57 and valve 58 into line 59 to cool the stream of heated oil discharged from heating element 48 to the desired temperature prior to its introduction 50 into subsequent portions of the system. The oil discharged from heating element 48 passes through line 59 and may be directed either through valve 60 into chamber 24 or through line 62 and valve 63 into chamber 21, or, if desired, 55 a portion of the heated oil may be directed to each of these zones.

Conditions may be so regulated in chamber 24 60 that a liquid residual product or a carbonaceous residual material or a product of intermediate nature such as asphalt or asphalt-like material 65 may be produced in this zone. Residual liquid, if produced, may be withdrawn from chamber 24 through line 64 and valve 65. In case a carbonaceous residual material is produced it may 70 be allowed to collect within chamber 24 to be removed after the operation of the process is discontinued or, if desired, a plurality of chambers such as 24, but not here illustrated, may be employed and may be operated either alternately or 75 simultaneously to permit prolonged operation of the process. In case asphalt or an asphalt-like material is to be produced in chamber 24 a plurality of such zones are preferably employed. Air, steam, other oxygen-containing gas or hydrocarbon gas or a combination of any of these

may be introduced into chamber 24 through line 66 to assist the asphalt making operation. This operation is commonly known as "blowing" and the chamber in which the asphalt is being blown is preferably isolated from the remainder of the 5 system during this operation.

Pressures employed within the system may range from atmospheric to superatmospheric pressures as high as 2000 pounds or more per square inch, the preferential range in the conversion zone being between 100 and 1000 pounds per square inch. Substantially equalized pressure 10 may be employed throughout the system or differential pressures may be utilized between the various elements of the system. Preferably reduced pressure is employed in the vaporizing chamber and in the succeeding fractionating, condensing and collecting equipment. Conversion 15 temperatures employed may range from 800 to 1200° F. more or less. Preferably the conversion 20 temperatures are between 850 and 950° F. in the primary heating element and between 900 and 1050° F. in the secondary heating element.

As a specific example of the operation of the 25 process of the present invention such as described and illustrated, a 24-26° A. P. I. gravity topped crude is the primary charging stock and comprises about 70 percent of the raw oil supplied to the process. The primary charging stock is subjected to a temperature of approximately 910° F. 30 under a superatmospheric pressure of about 200 pounds per square inch. This pressure is substantially equalized within the reaction chamber but is reduced in the vaporizing chamber to approximately 35 pounds per square inch. A secondary 35 charging stock of about 36 A. P. I. gravity and similar in characteristics to the reflux condensate from the fractionator of the system comprises about 30 percent of the total raw oil fed to the system and is subjected together with reflux 40 condensate from the fractionator to a temperature of about 960° F. under a superatmospheric pressure of approximately 300 pounds per square inch. A sufficient quantity of the reflux condensate is introduced into the stream of heated oil discharged from the secondary heating element to cool this stream of oil which is directed into the reaction chamber to a temperature of approximately 910° F. 45

This operation may yield approximately 65 percent of motor fuel having an anti-knock value 50 approximately equivalent to a blend of 50 percent benzol and 50 percent Pennsylvania straight-run gasoline. In addition about 25 percent of marketable fuel oil may be produced, the only other 55 products of the process being uncondensable gas and a negligible quantity of carbonaceous material.

In another operation similar to that above outlined except that the oil discharged from the 60 secondary heating element is not cooled by the introduction of reflux condensate and is introduced into the vaporizing chamber, a substantially dry carbonaceous deposit may be collected in the vaporizing zone as the residual product 65 of the system and an increased yield of motor fuel of somewhat higher anti-knock value may be produced. The gas production may also be increased.

By employing conversion conditions of an intermediate nature to those described in the above 70 examples and by blowing the residual product in the vaporizing chamber, for example, with steam, an asphalt-like residual product may be produced accompanied by gasoline yields generally some- 75

what lower than those obtained by non-residuum operation and somewhat higher than those obtained by operations in which marketable fuel oil is produced.

- 5 In another operation when the secondary charging stock comprising 40% of the total raw oil charge to the system was a Pennsylvania straight run gasoline having an anti-knock value of zero benzol equivalent and when heated to 1050° F. at 10 a pressure of 100 pounds per square inch in the secondary heating element discharging the same into the vaporizing zone 24 a 90% recovery by conversion or reforming of the gasoline may be obtained with an approximately 50% benzol anti- 15 knock value or an iso-octane anti-knock value of approximately 70. The other conditions may be the same as in the first example, a yield of approximately 55 percent gasoline being obtained from the topped crude making a total of approxi- 20 mately 70% based on the combined or total charge.

I claim as my invention:

1. In a process of hydrocarbon oil conversion wherein hydrocarbon oil is subjected to cracking conditions of temperature and pressure in a primary heating zone and the heated hydrocarbon mass passed to a reaction zone, the vapors and non-vaporous material being removed from said reaction zone to a vaporizing zone wherein vapors 30 are separated from non-vaporous material, said vapors being passed to a fractionating zone to condense insufficiently converted fractions thereof as reflux condensate, the improvement which comprises subjecting reflux condensate from said fractionating zone to reconversion conditions in a secondary heating zone, passing a portion of said reconverted mass to said reaction zone to commingle with the heated hydrocarbons from said primary heating zone, and passing the remaining portion of said reconverted mass to said vaporizing zone.

2. In a process of hydrocarbon oil conversion wherein hydrocarbon oil is subjected to cracking conditions of temperature and pressure in a primary heating zone and the heated hydrocarbon mass passed to a reaction zone, the vapors and non-vaporous material being removed from said reaction zone to a vaporizing zone wherein vapors 45 are separated from non-vaporous material, said vapors being passed to a fractionating zone to condense insufficiently converted fractions thereof as reflux condensate, the improvement which comprises subjecting reflux condensate from said fractionating zone in company with a secondary hydrocarbon charging stock to reconversion conditions in a secondary heating zone, passing a portion of said reconverted mass to said reaction zone to commingle with the heated hydrocarbons from said primary heating zone, and passing the 50 remaining portion of said reconverted mass to said vaporizing zone.

3. In a process of hydrocarbon oil conversion wherein hydrocarbon oil is subjected to cracking conditions of temperature and pressure in a pri-

mary heating zone and the heated hydrocarbon mass passed to a reaction zone, the vapors and non-vaporous material being removed from said reaction zone to a vaporizing zone wherein vapors are separated from non-vaporous material, said vapors being passed to a fractionating zone to condense insufficiently converted fractions thereof as reflux condensate, the improvement which comprises passing a portion of the reflux condensate to a secondary heating zone wherein reconversion 10 takes place, returning said reconverted hydrocarbons from said secondary heating zone in company with the remaining portion of said reflux condensate to said vaporizing zone wherein said mixture commingles with the heated hydrocarbon mass from the primary heating zone.

4. A hydrocarbon oil cracking process which comprises passing the oil in a restricted stream through a heating zone and heating the same therein to cracking temperature under pressure, 20 discharging the heated oil into a reaction zone maintained under cracking conditions of temperature and pressure, removing the vaporous and liquid reaction products as a mixture from the reaction zone and introducing the same into a separating zone maintained under lower pressure than the reaction zone, separating said mixture into vapors and residue in the separating zone, dephlegmating the vapors to condense insufficiently cracked fractions thereof, passing resultant reflux condensate through a second heating zone and subjecting the same therein to independently controlled cracking conditions of 25 temperature and pressure therein, delivering a substantial portion of the thus heated reflux 30 condensate directly from said second heating zone to said separating zone without prior passage through the reaction zone, and finally condensing the dephlegmated vapors.

5. A hydrocarbon oil cracking process which 40 comprises passing the oil in a restricted stream through a heating zone and heating the same therein to cracking temperature under pressure, discharging the heated oil into a reaction zone maintained under cracking conditions of temperature and pressure, removing the vaporous and liquid reaction products as a mixture from the reaction zone and introducing the same into a separating zone maintained under lower pressure than the reaction zone, separating said mixture into vapors and residue in the separating zone, dephlegmating the vapors to condense insufficiently cracked fractions thereof, passing resultant reflux condensate through a second heating zone and subjecting the same therein to independently controlled cracking conditions of 45 temperature and pressure therein, discharging a portion of the heated reflux condensate from the second heating zone into the reaction zone, discharging another portion of the heated reflux 50 condensate into the separating zone, and finally condensing the dephlegmated vapors.
